UNITED STATES PATENT OFFICE.

EUGENE TULLAR PEARL, OF NEW YORK, N. Y.

DESIGN FOR A SYRINGE.

SPECIFICATION forming part of Design No. 30,023, dated January 17, 1899.

Application filed December 23, 1898. Serial No. 700,173. Term of patent 14 years.

To all whom it may concern:

Be it known that I, EUGENE TULLAR PEARL, residing at New York, in the county of New York and State of New York, have invented § a new and useful Design for Syringes, of which the following is a specification, reference being made to the accompanying drawings, forming part thereof.

My design consists in the novel article of to manufacture shown and described.

Figure 1 is a view in side elevation of my design for a syringe, and Fig. 2 is a view in end elevation thereof.

As shown in the drawings, the essential 15 features of the design are as follows: The portion A appears cylindrical as viewed in Fig. 1 and tubular as viewed in Fig. 2, and is provided with a terminal enlargement B.

The portion C, encircling the portion A intermediate of its extremities, appears approximately bell-shaped in Fig. 1 and of circular cross-section end-on, as in Fig. 2, and a series of approximately V-shaped wings D within and surrounded by the mouth of the tube and radially disposed about its axis, as viewed 25 in Fig. 2.

I claim—

The design for a syringe as shown and described.

In testimony whereof I affix my signature 30 in the presence of two witnesses.

EUGENE TULLAR PEARL.

Witnesses:

CHARLES A. RYDER,
B. S. BETTMAN.
